UNITED STATES PATENT OFFICE.

AUGUST E. SCHUTTE, OF NORTHBORO, MASSACHUSETTS.

CONCRETE-MIXER.

1,367,719.

Specification of Letters Patent.

Patented Feb. 8, 1921.

Continuation of application Serial No. 781,287, filed July 26, 1913. This application filed November 17, 1919. Serial No. 338,729.

To all whom it may concern:

Be it known that I, AUGUST E. SCHUTTE, citizen of the United States, residing at Northboro, in the county of Worcester and State of Massachusetts, have invented certain new and useful Improvements in Concrete-Mixers, of which the following is a specification, reference being had therein to the accompanying drawing.

10 My invention relates to apparatus for mixing concrete or like heavy material which is difficult of manipulation.

The present application is a continuation of my original pending application for concrete mixer, filed July 26, 1913, Serial number 781,287, for the subject-matter shown therein which is present in the original pending application.

An important object of the invention is 20 to provide means for utilizing the rapid descent of the heavy material, by gravity, in comparison with the slower movements of the buckets or the like, in effecting an intimate mixture of the material, such buckets being employed to elevate the heavy material.

In the ordinary type of concrete mixer, a 30 rotary horizontal cylinder or mixing trough provided with blades is used. Into this the material to be mixed is conveyed by a lift or hopper and falls from above directly into the mixer. The material is elevated either by a suitable conveyer or by wheelbarrows. All these machines deliver the mixed material at a low point, and are cumbersome 35 and quite complicated and require a great deal of power to operate.

A further purpose of my invention is to 40 simplify such machines by doing away with the horizontal cylinder or mixing trough and instead providing a substantially vertical conveyer which is inclosed in a casing preferably adapted to serve as a support to the upper shaft of the conveyer, and at the 45 same time as a flue for carrying off the products of combustion, either from a furnace or oil burner connected with the bottom of the casing, so that all the hot gases are brought into direct contact with the material when lifted by the conveyer and also with the aggregate when dropped by the conveyer as it passes over the top shaft thereof. In fall-

ing, the aggregate separates more or less, thus allowing the hot air or products of combustion to come directly in contact with the individual particles. Thus the drying and heating are greatly facilitated.

The casing is preferably provided with a flooring at the bottom, into which the material is fed by a hopper or other suitable means. The whole may be mounted upon traction wheels with an engine for running the combined conveyer-mixer. It may further be used as a unit or in multiples. A number of conveyer-flues may be mounted on the same base, using the same source of heat to heat and dry the material, the heat being cut off from one flue and diverted through the adjacent flue while the mixing process is going on in the first flue.

My invention will be understood by reference to the drawings in which it is shown in its preferred form, two mixers being shown side by side and utilizing the same furnace.

Figure 1 is a vertical section through a unit of the apparatus, the conveyer being in elevation,

Fig. 2 is a vertical section at a right angle to Fig. 1, the conveyers being shown in elevation, and,

Fig. 3 is a horizontal section taken on line 3-3 of Fig. 1.

A is a casing divided by the partition A² into two chambers and having near its upper end take-up bearings b for the shaft B and at its lower end bearings c for the shaft C.

The bottom of the casing is floored to form retainers A² for the material to be treated. Its upper end, as shown, is contracted and terminates in stacks A³.

I prefer to use hoppers D by which to introduce the material into the retainers A², though it may be otherwise introduced if thought best. In the form of my invention shown there are mounted on the shaft B wheels B¹, B¹, preferably sprockets, two for each conveyer, and on the shaft C are mounted four corresponding wheels C¹, C¹, also preferably sprockets, and over these wheels pass the elevators or conveyers, each of which preferably comprises two sprocket chains E, E, between which are mounted buckets E¹. These buckets E¹ are prefer-

ably scoop-shaped and they are of such size and the shaft C is so located that they will scoop up material from the container and carry it up and over the shaft B and empty it so that it will fall back into the retainer.

The power is applied to the conveyers by a sprocket C² on the shaft C over which runs a chain c' connected to a suitable engine. By adjusting the take-up bearings b the slack of the sprocket chains E may be properly controlled.

To supply heat for drying the material I have shown a fire-box F connected by a forked pipe f with the lower end of the casing A, one pipe f entering on each side of the partition A¹. These pipes are each provided with a damper f¹ so that the products of combustion may be discharged into each chamber of the casing, as preferred. As shown, the fire-box is provided with grate-bars F¹, but instead it may be fitted with oil burning appliances of the kind well known, my invention relating to the conveying of the products of combustion or their heating equivalent, into the casing.

The casing is provided near its upper end with discharge openings, one for each chamber, of suitable size, which openings are ordinarily closed by a closure H in the form of a door, which is hinged at h. The door H may be moved by a swinging lever H¹, connected therewith by a link H². When the door H is closed, it is vertical and forms in effect a continuation of the vertical casing, but when the door is open, as shown in Fig. 1, it may be inclined and places an inclined trough h¹ in communication with said opening and the upper portion of the casing. Particular attention is called to the fact that the endless bucket elevators, upon their descending sides, are spaced from the casing A, providing a passage for the rapid descent of the concrete or the like, spilled at the top of the endless bucket elevators, upon such descending sides. This is important as the structure permits of the descending concrete or the like to travel downwardly faster than the buckets, such material passing the buckets freely.

During the operation of the apparatus, while the concrete or like heavy material is being mixed, the door H is retained closed. The conveyer being set in motion and the heated gas or air entering the casing or flue at the bottom, the material to be dried and mixed is fed into the hopper and is picked up by the buckets connected with the chains operating through the heating flue. The buckets discharge at the top, and the material drops down through the flue on the descending side of the conveyer, thus falling through the hot gases, to be again picked up at the bottom, elevated to the top, and discharged in a practically continuous stream, gaining in temperature on each elevation and

fall. The stacks A³ permit of the escape of the steam or moisture thrown off by the drying of the aggregates. After the material is sufficiently dried and heated, an amount of bituminous material (if the mixture is to be of a bituminous nature) is poured into the hopper, when the process of mixing proceeds in exactly the same manner as the drying which preceded it. The bitumen-coated material is elevated in hot elevator buckets, spilled at the top, picked up at the bottom and again spilled, the process continuing until an intimate mixture is produced, which is discharged through the chute h' when desired. The hopper is reloaded with wet material which is dried and mixed as before.

When the mixer is used for mixing Portland cement concrete, the heating system is disconnected, except in very cold weather, when it is necessary to dry or heat the stone, and the mixing proceeds in exactly the same manner as in the bituminous compound, with the exception that the water is poured into the hopper instead of the bituminous compound.

The apparatus is designed for mixing concrete either composed of Portland cement, stone and sand, or bituminous concrete composed of sand and bitumen, or sand, stone and bitumen, or any mineral aggregate and bitumen. This concrete, cementitious or bituminous, is a heavy material and difficult of manipulation. By virtue of the treatment of this heavy material, an intimate mixture is effected, in a peculiar manner. The heavy material is spilled at the top of the conveyer, and drops by gravity to the bottom of the casing into the container. The buckets travel slower than the falling heavy material, so that this material reaches the mass within the container, before its bucket approaches the same. The material thus dropped is again picked up by a bucket, beneath the discharging bucket, and such material thereby mixed with another and new portion of the total mass, and again distributed and mixed, not only by the forming of the material through the casing, but by the passage of the buckets through the mass, carrying with them the fallen material. In other words the material is dropped from the upper bucket to the bottom, where it is again picked up by the buckets, giving rise to a thorough mixing of the concrete, due to the fact that in its downward descent under the influence of gravity it travels faster than the buckets themselves, whereby the contents of the several buckets are intermingled during the process of mixing.

As the concrete is being spilled at the top of the conveyer, there is a tendency for the same to travel laterally, and by opening the closure H a part or all of the contents of the buckets will be discharged through the

chutes h' , when desired, at the end of the mixing process.

The details of construction of my device may of course be changed without departing from the spirit of my invention.

My device may be a stationary plant of as many units as desired or may be mounted on wheels so that it may be moved from place to place as desired. It is especially adapted 10 to the latter use because it is compact and by virtue of the reduction in the number of parts is of less weight than movable plants heretofore constructed.

Having thus described my invention, I 15 claim:—

1. Apparatus for mixing concrete or like heavy material difficult of manipulation, comprising a substantially vertical casing having a discharge opening near its top, a 20 traveling bucket elevator arranged within the casing and extending longitudinally thereof and having its descending side spaced from the casing for elevating the heavy material and spilling the same near 25 the upper end of the elevator upon the descending side of the elevator between the elevator and casing, said heavy material passing downwardly by gravity faster than the buckets, and means for controlling the discharge of the mixed heavy material through 30 the said opening.

2. Apparatus for mixing concrete or like heavy material difficult of manipulation, comprising a substantially vertical casing 35 provided at its lower portion with means for receiving and holding the heavy material, said casing being provided near its upper end with a discharge opening, means for controlling the passage of material through 40 the discharge opening, a traveling bucket elevator arranged within the casing and extending longitudinally thereof and having its descending side spaced from the casing to permit of the free downward passage of the 45 heavy material between the elevator and casing, said elevator picking up the heavy material and elevating the same and spilling such material near the upper end of the elevator upon the descending side of the elevator 50 between the elevator and casing, said heavy material passing downwardly by gravity faster than the buckets, and means to drive the elevator.

3. Apparatus for mixing concrete or like 55 heavy material difficult of manipulation, comprising a substantially vertical casing adapted for receiving and holding the heavy material, said casing having discharge means near its upper end, a traveling bucket elevator 60 extending longitudinally within the casing and having its descending side spaced from the casing to permit of the passage of the heavy material between the elevator and casing, said elevator being adapted to engage the heavy material within the lower end of the casing and elevate the same and spill such material near the upper end of the elevator, means to drive the elevator upon the descending side of the elevator 65 between the elevator and casing, said heavy material passing downwardly by gravity faster than the buckets, and means for supplying a heating medium into the casing.

end thereof and elevate the same and spill such material near the upper end of the elevator upon the descending side of the elevator between the elevator and casing, said heavy material passing downwardly by 70 gravity faster than the buckets, and means to drive the elevator.

4. Apparatus for mixing concrete or like heavy material difficult of manipulation, comprising a substantially vertical casing 75 adapted for receiving and holding the heavy material in the lower portion thereof, a traveling bucket elevator extending longitudinally within the casing and having its descending side spaced from the casing to permit of the passage of the heavy material between the elevator and casing, said elevator being adapted to engage the heavy material within the lower end of the casing and elevate the same and spill such material near 80 the upper end of the elevator and means to drive the elevator upon the descending side of the elevator between the elevator and casing, said heavy material passing downwardly by gravity faster than the buckets. 90

5. Apparatus for mixing concrete or like heavy material difficult of manipulation, comprising a substantially vertical casing adapted for receiving and holding the heavy material in the lower portion thereof, a 95 traveling bucket elevator extending longitudinally within the casing and having its descending side spaced from the casing to permit of the passage of the heavy material between the elevator and casing, said elevator being adapted to engage the heavy material within the lower end of the casing, and elevate the same and spill such material near the upper end of the elevator, means to drive the elevator upon the descending side of the elevator between the elevator and casing, said heavy material passing downwardly by gravity faster than the buckets, and means for supplying a heating medium in proximity to the heavy material being treated. 105

6. Apparatus for mixing concrete or like heavy material difficult of manipulation, comprising a substantially vertical casing adapted for receiving and holding the heavy material in the lower portion thereof, a traveling bucket elevator extending longitudinally within the casing and having its descending side spaced from the casing to permit of the passage of the heavy material between the elevator and casing, said elevator being adapted to engage the heavy material within the lower portion of the casing, and elevate the same and spill such material near the upper end of the elevator, means to drive the elevator upon the descending side of the elevator between the elevator and casing, said heavy material passing downwardly by gravity faster than the buckets, and means for supplying a heating medium into the casing. 115

4

7. Apparatus for mixing concrete or like heavy material difficult of manipulation, comprising a casing divided into a plurality of substantially vertical compartments 5 having means at their lower ends for receiving and holding the heavy material, traveling bucket elevators extending longitudinally within the compartments and having their descending sides spaced from the casing to permit of the passage of the heavy material between the elevators and casing, said elevators being adapted to engage the material within the lower ends of the compartments and elevate the same and spill 10 such material near the upper end of the elevators upon the descending sides of the elevators between the elevators and casing, said heavy material passing downwardly by gravity faster than the buckets, means to 15 drive the elevators, and means for produc- 20

ing heated gases and supplying the same to the compartments.

8. Apparatus for mixing concrete or like heavy material difficult of manipulation, comprising a substantially vertical endless 25 bucket elevator, means arranged near the lower end of the elevator to hold the material in the path of travel of the buckets and to catch the material spilled from the buckets near the top of the elevator upon the descending side of the elevator, said heavy material passing downwardly by gravity faster than the buckets, and means to drive the elevator.

In testimony whereof I hereunto affix my 35 signature in the presence of two witnesses.

AUGUST E. SCHUTTE.
